UNITED STATES PATENT OFFICE

140,927

DESIGN FOR A BAR OF TOILET SOAP

Sam J. Eisenberg, Winnetka, Ill., assignor to Excitement, Incorporated, Chicago, Ill., a corporation of Illinois

Application January 5, 1945, Serial No. 117,285

Term of patent 14 years

(Cl. D73—1)

To all whom it may concern:

Be it known that I, Sam J. Eisenberg, a citizen of the United States, residing at Winnetka, in the county of Cook and State of Illinois, have invented a new, original, and ornamental Design for a Bar of Toilet Soap, of which the following is a specification, reference being had to the accompanying drawing, forming a part thereof.

In the drawing:

Fig. 1 is a face view of a bar of toilet soap
showing my new design;

Fig. 2 is a side elevational view of the bar of toilet soap;

Fig. 3 is an end elevational view of the bar of toilet soap; and

Fig. 4 is a section taken on the line 4—4 of Fig. 1.

I claim:

The ornamental design for a bar of toilet soap,
substantially as shown.

SAM J. EISENBERG.
